UNITED STATES PATENT OFFICE.

ZACH J. MONTGOMERY, OF FRANKFORT, KENTUCKY.

INSOLE FOR SHOES.

1,340,906.

Specification of Letters Patent. Patented May 25, 1920.

Application filed May 3, 1915. Serial No. 25,470.

To all whom it may concern:

Be it known that I, ZACH J. MONTGOMERY, a citizen of the United States, residing at Frankfort, in the county of Franklin, and State of Kentucky, have invented certain new and useful Improvements in Insole for Shoes, of which the following is a specification, reference being had therein to the accompanying drawing.

10 This invention relates to improvements in welted boots and shoes and more particularly to the manner of attaching the upper and welt to the inner sole, and has for its object to produce a boot or shoe of this 15 character which shall combine maximum strength and flexibility and minimum weight resulting in reduced cost of manufacture.

Heretofore, it has been the common practice in the manufacture of boots and shoes to employ a relatively thick insole which is split or channeled around its edge to form the rib or lip to which the upper and welt are usually attached. This construction is 25 open to the objection that the employment of a thick insole renders the finished shoe less flexible than otherwise and also that the insole is weakened by channeling the same, such weakening resulting in the likelihood 30 of the upper and welt breaking away from the insole. In order to overcome the above objections, it is proposed in the present invention to use an insole of relatively thin and any suitable material which necessarily 35 will impart added flexibility to the shoe.

Furthermore, in contradistinction to the common method of forming the rib, the present invention contemplates the use of a 40 separate strip of canvas or other suitable material which is sewed or otherwise secured to the insole intermediate the longitudinal edges of said strip leaving said edges free to be turned up and secured together, preferably by cement, to form the rib to 45 which is secured the welt and upper of the shoe.

A further object of the invention is to facilitate the manufacture of the shoe by channeling or skiving the insole adjacent 50 the rib and on the inner side thereof, so as to guide the inseamer in the inseaming operation, and at the same time, reinforce and strengthen the rib where the latter is joined to the insole.

55 The inventive idea involved in this invention is capable of receiving a variety of

mechanical expressions, one of which, for the purpose of illustrating the invention, is shown in the accompanying drawing; but it is to be expressly understood that said drawing and the particular construction shown therein and described in the specification, are employed simply for the purpose of facilitating the description of the invention as a whole and not for the purpose of defining the limits of the invention, reference being had to the claims for this purpose.

Referring to the drawing:—

Figure 1 is a perspective view of the insole 70 with the rib attached;

Fig. 2 is an enlarged transverse section of the insole as shown in Fig. 1; and

Fig. 3 is a view similar to Fig. 2 with the 75 welt and upper attached.

In the drawing, 1 indicates the insole which is preferably made of a thin piece of leather of uniform thickness throughout, but which might be made of any other cheaper suitable material. This insole is not 80 provided with the ordinary slits or channels which form the rib or flange to which the welt and upper are usually attached, and the edge portion of the insole is consequently of the same thickness as the body portion there- 85 of, thus rendering it possible to employ an insole of considerably less thickness than is required for shoes constructed in the ordinary manner, and consequently, imparting a greater degree of flexibility to the shoe. 90

A strip of canvas or other suitable flexible material 2 is secured, intermediate its longitudinal edges, and preferably by a double row of stitching 3, to the insole 1 adjacent the edge thereof, as clearly illustrated in 95 Fig. 2. After the strip has been thus secured to the insole, the free edges 4 of said strip are turned up and a suitable adhesive 5, such as cement, is applied thereto in order to secure said edges together to form a rib or 100 flange 6, to which the welt and upper are sewed.

The insole 1 is further provided with a cut or channel 7 which forms a lip 8 adjacent to the rib 6 and on the inner side thereof, constituting in effect a facing for said rib. In manufacturing the shoe the edges of the upper, 9, are turned over the edge of the insole, and together with the welt 10, are sewed to the rib 6 by stitching through the 110 lip 8, and the said rib, as clearly illustrated in Fig. 3. The operation of attaching the

upper and welt is greatly facilitated by the employment of channel 7 as a guide for the inseamer and it will be apparent that after the upper and welt have been secured to the insole, the lip 8 will act as an additional reinforcement for the rib 6 and thus strengthen the connection between the upper and insole whereby the liability of breaking is obviated.

10 From the foregoing description, it will be apparent that insoles made in accordance with this invention not only reduce the cost of production of the finished shoes, but greatly strengthen the same and render 15 them more flexible than will the insole now commonly used.

Having thus described the invention, what I claim and desire to secure by Letters Patent is:—

20 1. An insole for shoes comprising a body portion and an edge portion of uniform thickness, a rib consisting of a strip of flexible material secured intermediate its longitudinal edges to said body portion, and 25 means associated with said rib and lying along and adjacent to the inner face thereof to form a guide for the inseamer.

2. An insole for shoes comprising a body portion and an edge portion of uniform 30 thickness, a rib consisting of a strip of flexible material secured to said body portion, and a facing for the rib constituting a reinforcement therefor and at the same time providing a guide for the inseamer.

35 3. An insole for shoes comprising a body portion of uniform thickness, and a rib consisting of a strip of flexible material secured to the body portion, said body portion being channeled to provide a guide for the inseamer.

40 4. A shoe having an insole comprising a body portion of uniform thickness, a rib consisting of a strip of flexible material secured intermediate its longitudinal edges to 45 the body portion, the latter being channeled

to form a guide for the inseamer, and an upper secured to said rib.

5. A shoe having an insole comprising a body portion of uniform thickness, a rib consisting of a strip of flexible material secured intermediate its longitudinal edges to the body portion, the latter being channeled on the inner side of said rib and adjacent thereto to provide a guide for the inseamer, and an upper secured to said rib. 50 55

6. An insole for shoes comprising a body portion of uniform thickness, and a rib consisting of a strip of flexible material secured to the body portion, the said body portion being channeled upon the inner side of said 60 rib to form a lip adapted to reinforce said rib when the upper and welt are sewed thereto.

7. An insole for shoes comprising a body portion of uniform thickness, and a rib consisting of a strip of flexible material secured intermediate its longitudinal edges to the body portion, the free edges of said strip being cemented together, said body portion being channeled to form a lip adapted to reinforce said rib when the upper and welt are 65 sewed thereto. 70

8. An insole for shoes comprising a body portion of uniform thickness, and a rib consisting of a strip of flexible material secured intermediate its longitudinal edges to the body portion, the free edges of said strip being cemented together, said body portion being channeled to form a lip adapted to 75 guide the inseamer when attaching the upper and welt to the insole, and also adapted to reinforce said rib when the upper and welt are 80 sewed thereto. 85

In testimony whereof I have affixed my signature in presence of two witnesses.

ZACH J. MONTGOMERY.
